Primary Examiner — Michael A. Pratt*(74) Attorney, Agent, or Firm* — The Webb Law Firm(57) **CLAIM**

The ornamental design for a shower handle, as shown and described.

DESCRIPTION

FIG. 1 is a bottom perspective view of a shower handle showing my new design in accordance with a first embodiment of the invention;

FIG. 2 is a bottom view thereof;

FIG. 3 is a top view thereof;

FIG. 4 is a left side view thereof, with the right side view being mirror image thereof;

FIG. 5 is a front view thereof, and

FIG. 6 is a rear view thereof.

FIG. 7 is a bottom perspective view of a shower handle showing my new design in accordance with a second embodiment of the invention;

FIG. 8 is bottom view thereof;

FIG. 9 is a top view thereof;

FIG. 10 is a left side view thereof, with the right side view being mirror image thereof;

FIG. 11 is a front view thereof; and,

FIG. 12 is a rear view thereof.

The broken line showing portion of the shower handle is included for the purpose of illustrating environment and forms no part of the claimed design.

1 Claim, 12 Drawing Sheets(56)
